UNITED STATES PATENT OFFICE.

ROY W. STEVENSON, OF HARVARD, ILLINOIS, ASSIGNOR TO CHARLES M. STEVENSON,
OF CHICAGO, ILLINOIS.

STANCHION.

Application filed May 21, 1921. Serial No. 471,401.

To all whom it may concern:

Be it known that I, ROY W. STEVENSON, a citizen of the United States, residing at Harvard, in the county of McHenry and 5 State of Illinois, have invented certain new and useful Improvements in Stanchions, of which the following is a description.

My invention belongs to that general class of devices particularly adapted for securing 10 cattle in their stalls, and has for its object the production of such a device that is simple and effective in operation, and which possesses peculiar advantages in the method and 15 convenience of operation. To this end my invention consists in the novel construction, arrangement and combination of parts herein shown and described, and more particularly pointed out in the claims.

In the drawings, wherein like reference 20 characters indicate like or corresponding parts,

Figure 1 is a side elevation, taken from the animal side, of a section showing two of my improved devices and method of 25 operation;

Figure 2 is a top plan view of the same;

Figure 3 is an elevation taken from the opposite side of the device;

Figure 4 is a section taken substantially 30 on line 4—4 of Figure 3;

Figure 5 is a top plan view of a fragment showing the details of construction;

Figure 6 is a similar view showing the several parts in different position;

Figure 7 is a sectional view taken substantially on line 7—7 of Figure 5;

Figure 8 is a sectional view taken substantially on line 8—8 of Figure 5;

Figure 9 is a similar view taken on line 40 9—9 of Figure 5;

Figure 10 is a similar view taken on line 10—10 of Figure 5;

Figure 11 is a cross sectional view taken substantially on line 11—11 of Figure 1; and

Figures 12 and 13 are sectional views taken substantially on lines 12—12 and 13—13 of Figure 1.

In the drawings, 1 indicates the floor of the stall, which at the other end, or the end 50 near the animal's head, is preferably raised to form a base wall 2, carrying the stanchions. 3 indicates a division bar between the stalls separating the animals, and also serves as a brace to rigidly support the structure 55 carrying the stanchions. 4—4 are substan-

tially vertical tubular members which at their lower ends are rigidly connected to the raised base 2, and above the stall divisions 3 are rigidly connected. In the preferred construction shown, the members 4 extend outwardly from each other near the bottom and are thence inclined upward toward each other, at or near their meeting point being bound together by a suitable coupling member 5 (Figures 1, 3 and 11). The inclination of these two members 4 is substantially parallel with that of the approximate stanchion bars 4 when the latter are open, forming what is sometimes called a "sure stop" to prevent the animal passing its head between 70 said supports 4 and the stanchion as the animal enters the stall (see dotted lines, Figures 1 and 3.) Above the coupling 5 the two bars or tubes 4 are extended upward to the desired height, and at the upper end 75 carry the member 6 which secures the two parts 4 together and rigidly engages them with a horizontal bar 7. The bar 7 is preferably angular or irregularly formed so as to maintain its position and properly and 80 non-rotatively support the various parts in suitable alignment. The structure thus far described is rigid in its nature and constitutes the frame work of my improved device.

8—8 are the stanchion bars which are 85 supported and depend from the top structure. These are ordinarily metal tubes and may, if desired, be provided with wood or other suitable linings 9 upon the inside. The members 8 are pivotally supported at 90 the top on members 10—10^a, which are slidingly mounted upon the horizontal bar 7. The lower ends of members 8—8 are pivotally connected to a link member 11 so as to allow the upper ends to be separated as indicated in dotted lines, said link member being provided with an extending boss 12 which is loosely positioned within a comparatively large recess 13 formed in the base 2, so as to allow the lower end of the 100 stanchion to have a limited movement transversely the stanchion, and at the same time permit of a limited pivotal movement of the entire stanchion when it is closed, providing flexibility of movement very advantageous in devices of this character. A casting 14 may be secured upon the support 2, if desired, to restrict the movement and prevent undue wear.

At suitable points upon the horizontal bar 110

7 are rigidly secured guides 15 (Figures 5 and 10) which slidably support a master rod or bar 16. These guides 15 are positioned between the meeting or approximate upper ends of the stanchion bars 8, and when all are suitably locked, serve as a stop to prevent movement upon the bar 7.

At one end of the section a bell-crank lever 17 is pivotally supported at 18 and is connected by a link 19 to the sliding master bar 16 (Figures 1, 2 and 3). The operation of the lever, therefore, serves to control the movement of the master bar 16 back and forth in its guides.

15 Rigidly secured adjustably upon the bar 7 near each stanchion, but on the side opposite the lever 17, is a sleeve or collar 20, slidable on the bar 7, and which at a point preferably, below the bar 7 pivotally supports a lever 21 at a point between its ends as at 22. A link 23 for each stanchion is pivotally connected as at 24 with the approximate end of the lever 21, and at its other end is connected to the supporting parts 10^a so that 25 as the master bar 16 is longitudinally moved, it will oscillate the lever on its pivotal support. The opposite end of the lever which extends upon the other side of the bar 7 is pivotally connected as at 25 to a link 26 30 which is extended and pivotally connected as at 27 to the part 10 of the stanchion nearest to the lever 17 or on the opposite side of the dividing piece 15.

The master bar 16 is provided also with 35 one member of a locking device for each stanchion. This member of the locking device is firmly secured to the master bar and is carried thereby in its movements. In the preferred form shown, a latch 40 is rotatably mounted upon the bar 16 and is provided with a slotted end 28 which is adapted to be brought into engagement with a pin 29 or equivalent member carried upon the supporting member 10^a of the stanchion bar 40 opposite to the lever 17. It is obvious therefore that the swinging of the lever 17 will cause the oscillation of the bar 16, and the members 10^a with which the locking member 40 is connected. This will oscillate the 45 lever 21, which at its opposite end, by means of the link 26, will throw the cooperating member 10 in the opposite direction, moving the top of the members 8 apart, as indicated in the dotted lines, and opening the 50 stanchion. This would be the operation unless the two members 10 were locked together. In the preferred construction, a locking member is provided for that purpose, when desired to prevent accidental 55 separation of the parts and for the further purpose of locking certain stanchions firmly together, while other stanchions may be opened by operation of the bar.

In the simple form of locking member 60 illustrated, a slotted bar 30 is pivotally sup-

ported as at 31 upon one of the members, as 10, while the cooperating member is provided with a cooperating pin 32. It is thus apparent that if the locking member 30 is engaged with the pin 32 and the locking member 40 is disengaged from the pin 29, the operation of the lever will reciprocate the bar 16 without affecting the stanchion bars locked together, as indicated at the left in full lines on Figure 1. On the other hand, if the locking member 30 is disengaged from the pin 32, while the latch 40 engages the pin 29, a reciprocation of the bar 16 by the lever will oscillate the lever 21 upon its pivot, and through the link connection described, will move the parts 10 apart from or toward each other and the support 15, as indicated in Figure 6.

The advantages of this form of construction are many. In the first instance, when the tops of the stanchion bars are locked together as indicated in Figure 2, the danger of accidental disengagement and opening is very remote, and a degree of security is gained which is important in this line of industry. The bar 17 also throws by its center 18 in such manner as to add to this security. If now it is desired to release all of the cattle held in the section, the attendant moves along on the opposite side and disengages the several latches 30 from their cooperating pin 32, as indicated in full lines in Figure 6 and in dotted lines at the right in Figure 1 and the left in Figure 3. The operation of the lever will then simultaneously open all the stanchions, as indicated in dotted lines, and release the cattle. If on the other hand, it is desired to release but a portion or a part of the cattle thus confined, the attendant will simply operate the latch 30 upon those stanchions where it is desired to release the cattle, at the same time disconnecting the latch 40 from its engaging member 29. The movement of the bar will then serve to open the stanchion where the latch 30 is disconnected, while all others will be maintained in a closed and locked position as indicated in Figure 1, where the open stanchion is shown in dotted lines.

If at any time it is desired to release but a single animal, the attendant may release both latches 30 and 40, when the upper ends of the stanchion bars may be readily moved apart and the animal released without in any way interfering with the other connections. Likewise, a single animal may be secured by reversing the operation just described.

When the stanchions are secured together as indicated in full lines, a limited pivotal movement of the stanchion is permitted by reason of the pivotal connection of the upper part of the stanchion with the supporting members 10-10^a, which is not interfered with by the loose connection at the lower

end of the stanchion. When the stanchion is open however, as indicated in dotted lines, it is supported at three points as indicated, and these points are somewhat widely separated.

5 The pivotal function in this position is substantially eliminated, rendering it impossible for the stanchion to turn upon a vertical pivotal point which might interfere with the proper engaging of the neck of the animal therewith. As before stated, when in the open position, the inclination of the stanchion bar 8 and the supports 4 are such as to form a "sure stop" and to insure the proper positioning of the animal's neck in 15 alignment with the stanchion.

It is obvious that an equivalent construction of many parts will serve the same purpose, the details above simply describing the preferred form illustrated.

20 Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

30 1. In a device of the kind described, a stanchion structure comprising a base, vertical supports, and a transverse bar near the top, all operably secured together, in combination with a stop member secured to the 35 transverse bar, a block slidably mounted on the bar on each side of the stop, a depending stanchion bar pivotally supported on each block, with their lower ends pivotally connected to a link, said link being loosely and 40 rotatably engaged with the base, a master bar slidably supported parallel to the transverse bar, means for detachably locking the master bar to one of the sliding blocks, a lever pivoted between its ends directly on 45 the transverse bar, with one end pivotally connected to said last-mentioned sliding block and the other end pivotally connected

to the other sliding block, whereby the movement of the master bar will serve to open or close the stanchion.

50

2. In a device of the kind described, a stanchion structure comprising a base, vertical supports, and a transverse bar near the top, all operably secured together, in combination with a pair of blocks slidably mounted on the transverse bar, a depending stanchion bar pivotally supported on each block, with their lower ends pivotally connected to a link loosely maintained in the base, a master bar slidably supported parallel to the transverse bar, means for detachably locking the master bar to one of the sliding blocks, a lever pivoted between its ends directly on the transverse bar with one end pivotally connected to said last- 60 mentioned sliding block and the other end pivotally connected with a link extending to and pivotally engaging the other sliding block, and means independent of said first mentioned means for detachably locking the 70 sliding blocks together.

65

3. A device of the kind described comprising a supported horizontal bar, a pair of stanchion supporting blocks slidably mounted on the bar, in combination with a 75 longitudinally movable bar in proximity to the supporting bar, means for detachably locking the second mentioned bar to one of said sliding blocks, a sleeve slidably mounted on the first mentioned bar, means for adjustably securing said sleeve thereon, a lever pivotally supported by the sleeve, with one end pivotally engaged with said last mentioned sliding block and the other end operatively connected with the other sliding 85 block.

80

In testimony whereof, I have hereunto signed my name in the presence of two subscribing witnesses.

ROY W. STEVENSON.
